UNITED STATES PATENT OFFICE.

DONALD BARNS MORISON, OF HARTLEPOOL, ENGLAND.

APPARATUS FOR HEATING BOILER FEED-WATER.

1,313,199.

Specification of Letters Patent.

Patented Aug. 12, 1919.

Application filed July 19, 1917. Serial No. 181,602.

To all whom it may concern:

Be it known that I, DONALD BARNS MORISON, a subject of the King of Great Britain and Ireland, residing at Hartlepool, in the county of Durham, England, have invented the Improvements in or Relating to Apparatus for Heating Boiler Feed-Water, of which the following is a specification.

The invention is an improvement in or modification of the invention described in Patent No. 1108210 of 1914, and also relates to the apparatus described in Patent No. 1148182 of 1915.

In the patents above referred to, the apparatus comprises a primary heater, and a secondary heater of the direct contact type, the steam only flowing to the secondary heater when a predetermined pressure is reached in the primary heater.

According to the present invention, the primary heater, or the heating steam supply, is placed in free communication with the secondary heater by means of a passage, the arrangement being such that at low loads when the heating steam is relatively small in quantity, practically no resistance is offered to the flow of steam to the secondary heater, so that under such conditions the back pressure on the exhaust system is reduced. The passage, or it may be a heating nozzle or the like in the secondary heater to which the passage leads, is of such area, or is provided with means capable of such regulation, that the quantity of steam required to heat the water supplied to the secondary heater up to a desired temperature can, when available, be delivered thereto, the arrangement being such that when the steam available for use in the secondary heater is greater than is required for the desired temperature therein, the pressure in the primary heater rises until a predetermined limit is reached when the surplus steam passes into the condenser or suitably elsewhere.

Although the present invention possesses the advantages above referred to, it none the less embodies the arrangement in my prior patents, whereby a predetermined pressure must be reached in the primary heater before steam passes from the heating system into the condenser or elsewhere.

Whether the device through which the steam enters the secondary heater, consists of a submerged nozzle or other means, as for instance a perforated plate placed in a water

spray chamber, such device may be constructed in a manner and of such proportions that it will pass the required quantity of steam to heat a predetermined quantity of water flowing through the secondary heater to a desired temperature. For example, a nozzle may be employed and placed within a submerged pipe or water circulating tube, and provided with multiple outlets arranged to discharge jets of steam in the direction of the axis of the pipe or tube, the supply of water for the heating nozzle being preferentially taken from a filter chamber into which the feed water flows.

The accompanying drawings illustrate apparatus in accordance with my invention.

Figure 1 is a diagrammatic view of one form of feed water heating apparatus.

Figs. 2 and 3 show in detail a form of heating nozzle for use in a secondary heater which contains feed water in bulk, and Fig. 4 is a view similar to Fig. 1 of a modified form of feed water heating apparatus.

The similar parts are referred to by the same letters of reference.

With reference to Fig. 1, the primary heater *a* and condenser *c* may be connected to the heating steam supply system in any convenient manner, but in order to render the drawing as simple as possible they are shown connected directly to the heating steam supply pipe *e*; a loaded valve *g* being placed between the condenser *c* and pipe *e*.

The primary heater *a* or the heating steam supply *e* is placed in free communication with the secondary heater *b* by a passage *p* which leads from the three way cock *q* which is connected to the primary heater *a* by pipe *p*¹ and to the heating steam supply by pipe *p*². The quantity of steam delivered through the passage *p* from the primary heater *a* or the heating steam supply *e* to the secondary heater *b* is controlled by the capacity of the nozzle *r* or by a shut-off valve or cock *l* so that the steam supply to the secondary heater and the temperature of the water passing therethrough is at all times capable of regulation. The drainage water from the primary heater is discharged through the pipe *s* into the secondary heater *b*, or any other convenient means for discharging the water from the primary heater may be employed.

In the arrangement referred to, the quantity of steam required to heat the water supplied to the secondary heater *b* up to a de-

sired temperature, can, when available, be delivered thereto through the cock *g*. When, however, all the available steam is not employed in the heaters, the surplus steam 5 passes through the loaded escape valve *g* into the condenser.

Fig. 2 shows in sectional elevation the nozzle *r* shown in Fig. 1; Fig. 3 being a cross section on a larger scale on the line A—A 10 in Fig. 2. The nozzle is in the form of a stepped cone, each step *d* being of toothed formation, the teeth having steam outlet passages *f* which communicate with the steam space *j* in the nozzle, the spaces *i* between the teeth forming intermediate passages 15 for the water which is circulated by the inducing action of the discharged steam. The nozzle is placed within a pipe or circulating tube *h* having water inlets *m* and a common water outlet *n*. The nozzle described may be arranged in various ways but in the illustration it is shown contained in a small compartment in the interior of the secondary heater, the wall *o* having a circular opening *t* through which the pipe *h* projects, and another opening *u* between the wall and the bottom of the heater. Feed water is admitted to the compartment through the pipe *k*, and entering the inlets 20 *m* is discharged through the outlet *n* into the main chamber of the secondary heater *b*, from which it is drawn by a feed pump *A* (see Fig. 1) and discharged into the surface heater *a*, from which it passes to the boilers. 25 In addition to the circulation of the entering feed water in the manner described, the body of the water in the tank may be continuously circulated through the openings *t* and *u* in the manner indicated by the arrows. 30 Fig. 4 is a modification of Fig. 1, the difference being that the secondary heater *b* in Fig. 4 is of the water spray type. In Fig. 4, the secondary heater *b* consists of a closed vessel having a water inlet pipe *h* from 35 which the feed water is delivered over the perforated plate *w* by which it is sprayed in the interior of the heater. Steam from the primary heater *a* enters by valve *l* and is discharged into the chamber *y* formed 40 between the perforated plate *x* and the side of the heater *b*. From the chamber *y* the steam flows through the perforations in the plate *x* and is condensed by the water 45 sprayed from the plate *w*.

50 55 What I claim is:—

1. Feed water heating apparatus comprising a primary steam heater receiving steam from a heating steam supply system and arranged on the discharge side of a feed pump, 60 a secondary steam heater arranged on the suction side of said feed pump, a passage placing the heating steam supply or the pri-

mary heater in free communication with a nozzle in said secondary heater, said nozzle being placed in a submerged pipe or circulating tube and provided with multiple outlets arranged to discharge jets of steam in the direction of the axis of said pipe or tube, means for limiting the quantity of steam flowing through said nozzle to that required 65 to heat a predetermined quantity of water flowing through the secondary heater to a desired temperature, and a loaded valve through which steam not utilized in the heaters passes from the heating system into 70 a condenser when a predetermined pressure is reached in the primary heater.

2. Feed water heating apparatus comprising a primary steam heater receiving steam from a heating steam supply system 80 and arranged on the discharge side of a feed pump, a secondary steam heater arranged on the suction side of said feed pump, a passage placing the heating steam supply or the primary heater in free communication with 85 a nozzle in said secondary heater, said nozzle being placed in a submerged pipe or circulating tube and constructed in the form of a stepped cone, each step having a tooth formation with steam discharge outlets from 90 the teeth and intermediate passages for the flow of water between the teeth, and a loaded valve through which steam not utilized in the heaters passes from the heating system into a condenser when a predetermined pressure is reached in the primary heater.

3. Feed water heating apparatus comprising a primary steam heater receiving steam from a heating steam supply system and arranged on the discharge side of a feed pump, 100 a secondary steam heater arranged on the suction side of said feed pump, a passage placing the heating steam supply or the primary heater in free communication with a nozzle in said secondary heater, the latter 105 having internal compartments into one of which the water to be heated is delivered, a submerged pipe or circulating tube extending through an opening in the wall separating two of said compartments, the nozzle being placed in said pipe or tube for the purpose of circulating the heated water there-through into the adjoining compartment, and a loaded valve through which steam not utilized in the heaters passes from the heating system into a condenser when a predetermined pressure is reached in the primary heater.

Signed at London, England, this 28th day of June, 1917.

DONALD BARNES MORISON.
